DISPLAY APPARATUS

Frank S. Hebden, Peoria, Ill.

Application November 14, 1935, Serial No. 43,702

16 Claims. (Cl. 40—32)

This invention has reference to display apparatus, particularly to a device for operating moving signs, news bulletins, or the like.

Moving signs of certain types are not new. A common structure employed comprises an endless strip of paper, or the like, arranged to run as a belt over upright pulleys, one or more of which is driven so as to cause the strip to move continuously past an opening in the casing of the device. The pulleys may be arranged in such a manner as to carry several strands of the sign belt, and one of the pulleys is usually made movable and tensioned so as to take up slack and hold the belt taut.

Tautness of the belt is required in such devices in order to hold the belt in firm contact with the driving pulley so as to ensure satisfactory driving friction. Further, if the belt is not held taut it will sag and have an unsightly appearance.

In devices of this character, economic considerations force the use of paper, or other low cost material, for belts and this is generally quite fragile. Such fragile material, when held in tension and continuously run over relatively small pulleys rapidly deteriorates and breaks. Further, in practical use the distance between pulleys, or in other words the length of visible sign, must be made relatively short, otherwise the tension required to hold the suspended length taut and upright would be greater than the tensile strength of the belt material.

It is a general object of my invention to provide a moving sign device in which the above noted limitations and disadvantages are absent, one that may be made of any desired length and height so as to be adapted for use in large store windows, on long building walls, billboards and the like, and with which paper, or other low cost material, may be successfully used.

An additional object is to provide a mechanism comprising a driven conveyor and a sign strip which rides thereon so as to expose the text of a sign printed on the strip in a moving manner.

Another object lies in the provision of a conveyor device for operating a moving sign, and a sign strip removably riding thereon which includes means for increasing friction between the sign strip and conveyor whereby the strip is caused to move in substantially perfect accompaniment with the conveyor.

A further object is to provide a conveyor with a sign strip riding thereon without geared engagement between them and means for pre-

venting unwanted movement of the strip with respect to the conveyor.

Other objects and advantages will appear in the following description and accompanying drawings in which:

Fig. 1 is a plan view showing a mechanism embodying my invention, the same being shown without covers;

Fig. 2 is a side elevational view showing the mechanism as arranged in Fig. 1 with part of the cover broken away;

Fig. 3 is an enlarged sectional elevational view taken on line 3—3 in Fig. 2;

Figs. 4, 5, 6, 7, and 8, are fragmental elevational and plan views showing details of structure to be referred to;

Fig. 9 is a sectional elevational view similar to Fig. 3 showing a modified structure to be explained;

Figs. 10 and 11 are side and end elevational views respectively showing a modified structure which will be described, Fig. 11 being taken on line 11—11 in Fig. 10;

Fig. 12 is a plan view showing another modification of structure;

Fig. 13 is a fragmental side elevational view showing details of the arrangement in Fig. 12;

Fig. 14 is a detail plan view taken on line 14—14 in Fig. 13;

Fig. 15 is a plan view showing an arrangement of mechanism to be described;

Fig. 16 is an end elevational view taken from line 16—16 in Fig. 15;

Fig. 17 is a fragmental elevational view to be referred to; and

Figs. 18 and 19 are plan and side elevational views showing devices to be described.

In carrying out my invention I provide a conveyor mechanism, which may have any desired form or length, herein shown as including a base member 10 upon which the conveyor is supported.

The conveyor mechanism consists of a belt 11 reefed over end idler pulleys 12 and horizontal reverse pulleys 13 and 14. Pulleys 12 are supported by stands 15, pulley 13 is supported by stand 16 and pulley 14 is supported by a stand 17 all of which stands are secured to the base 10. The idler and reverse pulleys are so disposed that the belt 11, which in the Fig. 1 and 2 arrangement is flat, may be run upon them in such arrangement that the flat sides of its two long strands lie horizontal and parallel as shown.

The belt is driven by a motor 18 attached to base 10, through a worm 19 meshing with a worm

gear 20, which latter is affixed to the shaft of pulley 14.

The long strands of the belt between pulleys 12 may be supported against sagging by any suitable means, such as rails 21 supported upon arms 23 of stands 22.

The described arrangement provides a conveyor having two flat parallel strands running in opposite directions.

10 Disposed so as to ride upon the belt is a strip of material 24, such as paper, celluloid, or the like, hereinafter called a sign strip.

The sign strip stands upright and substantially edgewise with respect to the belt as best shown in Fig. 3 and is supported in this position by means of upper and lower guide elements which are here shown as comprising the inturned edges of cover elements 25 guiding the lower edge of the strip on the outside and the outer edges 20 of a plate 26, supported on stands 22, guiding the lower edge on the inside.

The top edge of the strip is guided by means of a slot formed between the downturned edges of plates 27 and 28, the edges of plate 27 guiding the strip on the outside and plate 28 guiding on the inside. The plates are supported on stands 22.

The sign strip is usually made endless and is of such length that the ends, or return bend portions, lie outwardly beyond pulleys 12 so that 30 the strip, at the points where it is bending for the return run, overhangs and is not in contact with belt 11. The material of which the sign strip is made usually has sufficient stiffness to make it self supporting in the overhung portions.

35 The utility of the arrangement just described will become apparent when it is considered that the expansion characteristics of material from which sign strips are usually made are highly responsive to atmospheric changes, chiefly temperature and humidity, and thus a strip of any sizeable length may expand or contract an appreciable amount from day to day.

With the arrangement shown it will be apparent that since the ends of the strip are unconfining the length of the strip may vary through a wide range without in any way affecting the relationship between the strip and conveyor. Further, when a strip is made up for placement on the conveyor it is not necessary that its length 50 be made with extreme accuracy and this obviously facilitates the making of strips.

It may also be noted that a strip, arranged and operated as above is at all times free from tensile stress, thus permitting the use of low cost material, such as paper, for the strips.

Obviously, one of the most valuable features of a device of this kind lies in the facility and low cost involved in making frequent changes in the sign strip. Both the cost of the material of 60 the strip itself and the labor required to replace an old strip with a new one must be held at a minimum if the device is to find wide public acceptance and sale. It is to this end that the above structure and arrangement lends itself.

65 The belt 11 is operated by motor 18 in the obvious manner, and the sign strip having its two long reaches resting upon the strands of the belt is carried in accompaniment with the belt.

In Fig. 2 I show a portion of cover 25 and plates 70 27 and 28 in position. The cover and outer plate 27 obscure all parts except a "sight" portion and the message printed on the sign strip is exposed in this open portion. With the conveyor running 75 the sign is obviously kept in motion which ren-

ders it highly attractive to the eye, and the message is continuously and endlessly exhibited.

In a sign of any considerable length, friction between the guide elements and the strip is likely to be considerable. Also, a certain amount of 5 resistance and frictional effect may be present due to static electricity often developed when paper or celluloid are used under the conditions noted.

For practical purposes, when a plain strip of 10 sign material is disposed with its edge resting upon a moving conveyor, there may not be sufficient tractive effect between the strip and conveyor to overcome the guide and static resistance above noted. For this reason the sign strip will 15 not accompany the conveyor in its movement in a satisfactory manner.

To provide suitable tractive effect to promote unitary movement of the conveyor and sign I utilize various means of preparing the sign strip 20 so that it will have more positive contact with the conveyor.

In Figs. 1 to 4 I show one means of accomplishing the result. Spaced along the lower edge of the strip are small wire members 29 which are 25 formed so as to be fastened in the strip as shown and have downwardly extending leg portions which lie in contact with the surface of the conveyor belt. The practical effect of this is thought obvious. The ends of the legs nestle somewhat 30 into the belt fabric and the strip is thus urged with considerable force to accompany the belt.

It will be noted however that the legs of members 29 cannot become attached to the belt with sufficient firmness to prevent free separation at 35 the points where the belt departs from the strip over idlers 12, and during the turning movement of both the belt and strip, the strip is free and independent of the belt.

In Fig. 5 I show an optional means of increasing 40 tractive effect between the belt and strip. In this arrangement I use numerous relatively small split pellets, or rivets 30, of heavy material such as lead, secured to the lower edge of the strip. The members 30 are made of sufficient weight 45 to considerably increase the total weight of the strip whereby to increase the tractive effect without altering the running conditions of the strip.

In cases where the sign strip is relatively narrow either of the foregoing methods of increasing 50 tractive effect may be found satisfactory. Numerous other means may be utilized without alteration of the principle involved.

For example, under certain conditions of use and arrangement of structure it may be found 55 practicable to prepare the conveyor belt in some special manner, such as by impregnation with chemicals to increase friction or forming sharp corrugations in the surface of the belt, as shown in Fig. 17. In instances where such preparation 60 of the belt is found to work satisfactorily the special means on the sign strip may be dispensed with. It is desirable to use some special means of increasing tractive effect. The particular method used is not important.

65 In cases where a relatively wide sign strip is used, when the width is so great that the material of the strip is not inherently self supporting, I may utilize stiffener strips 31, as shown in Figs. 6 and 7. These may be made from any suitable material such as steel or bamboo. They are attached to the strip by any suitable means and are spaced as required. In the Fig. 6 arrangement the stiffeners have pointed ends 31' and they thus serve the double purpose of stiffening 75

and increasing traction. In the Fig. 7 arrangement the stiffeners are trimmed flush with the edges of the strip and members 29 are attached for traction. Other means of stiffening may obviously be used without alteration of principle.

In Fig. 9 I show an arrangement similar to Fig. 3 wherein a round conveyor belt 32 is used in place of the flat belt 11. When using a round belt it becomes necessary to use a modified form of traction member in place of members 29. A practicable form is shown in Fig. 8 wherein a wire form 33 having a broadened base length is attached to the sign strip. The base portion rests crosswise of the belt as shown and forms a practicable means for riding a sign strip on a round belt.

The foregoing has described an arrangement of conveyor and sign generally covered in Figs. 1 and 2.

In such an arrangement the traction members 29, 30, 31', etc., obviously provide means whereby the sign strip is moved in substantial unity with the conveyor belt. In any non-fixed association of the strip and belt there may be a certain amount of creepage due to various influences. This creepage may obviously be unequal as between the two long reaches of the sign and thus it would be possible for one side to gain or lose on the other. Continuation of such movement would eventually result in one return bend running up and afoul the guide elements.

To prevent such occurrence, idler pulleys 34, supported on stands 35 may be disposed within the loops of the sign strip. These, it will be noted, are so placed that the loops of the strip lie beyond and free from engagement with them so that when the strip lies in normal position the idlers have no function to perform. However, if the strip shifts its position to a sufficient extent an idler will prevent continuance of the movement and thus prevent fouling.

In Figs. 18 and 19 I show a modification of the above described idler arrangement. In the modified arrangement idlers 34 are replaced by idlers 34' which are arranged to turn eccentrically on stands 35, as shown. Small lugs 36 extend below the idlers and are resiliently engaged with spring members 37 attached to stands 35. The contact pressure between lugs 36 and the springs is only sufficient to prevent loose rotation of the idlers and the lugs are so disposed that engagement exists only when the idlers are disposed as shown in Fig. 19. Idlers 34' are so placed that the sign strip loops normally pass beyond and around them with a space between when the idlers rest with their high sides lying toward the center of the mechanism. As above noted they are lightly held in this position by the springs 37.

When creepage and shifting of the sign strip progresses far enough to place the strip in engagement with an idler, on its low side, the idler is caused to rotate whereby the high side is placed on the opposite side of its center and the sign strip is forced backwardly to assume its normal position with respect to the belt. After the high side of the idler once passes the loop it will normally continue rotation to its original position and the strip is thereafter free as before. Thus, if the sign strip creeps regularly it will be periodically automatically readjusted.

In Figs. 10 to 12 I show still another modification of the mechanism. In this arrangement the mechanism is similar to those already described

with the exception that a square belt 37 is used in place of the flat belt 11.

As will be obvious, a square belt has the advantage that it may have a satisfactorily broad top surface upon which to support the sign strip, and at the same time it may be trained around a pulley lying in a horizontal plane. A practicable arrangement is shown. It will be noted that less mechanism is required and that the end loops of the sign strips are free to move outwardly over the surface of the belt and beyond so that the strip is free to expand or contract without alteration of the normal conditions of operation.

The sign strip need not necessarily be made endless. Figs. 13 and 14 are fragmentary views illustrating that a relatively short strip may be used successfully.

The outer guide elements at the top and bottom of the strip are extended around to join the long side elements 38 and 39 and thus form a loop guide whereby the end of a sign strip approaching in the direction of the arrow A in Fig. 14, is engaged by the curved guide and is diverted to follow a reverse direction whereby the free end B is returned and placed upon the opposite belt. From then on the operation is the same as has already been described until the opposite end of the conveyor belt is reached, where a reverse turn is again made in the same manner.

In Figs. 15 and 16 I show an arrangement which permits the use of extra length of sign strip.

The mechanism is substantially the same as that already described with the exception that the conveyor belt is arranged to have four long strands instead of two and the sign strip is also arranged with four strands.

Strand C of the belt is trained over idler pulleys 40, corresponding to idlers 12, thence around an idler 41 corresponding to idler 13, over the opposite idler to the opposite end of the mechanism to form strand F which is returned as strand H to strand D, over drive pulley 42 corresponding to pulley 14, back as strand E and return to strand C through strand J. The conveyor is operated by motor 43.

Strands C, D, E and F are obviously the top or carrying strands. They move in directions indicated by arrows.

The sign strip is arranged to ride on strand C, around loop K, over strand F, around loop L over strand E, around loop M to strand D, thence around loop N to strand C.

Safety idlers 34 or 34' may be used if necessary.

The extra length of sign strip absorbed by the inner strands D and E obviously permits a relatively long message to be carried by the strip without increasing the over-all length of the mechanism. The number of strands may be increased as desired.

It is to be noted that in none of the arrangements described is the sign strip placed in tension, with the exception of the small pull which might be brought about when the strip engages safety idlers 34 or 34', as described.

What I claim is:

1. A moving sign device comprising a moving conveyor with a sign strip riding edgewise thereon and means for driving the conveyor, the strip being disposed in a substantially straight line lengthwise of the conveyor with all parts of the strip moving at the same linear speed.

2. A moving sign device comprising a moving conveyor with a sign strip riding edgewise there-

on, means for holding the sign strip in edgewise arrangement and means for driving the conveyor, the strip being disposed in a substantially straight line lengthwise of the conveyor with all parts of the strip moving at the same linear speed.

3. A moving sign device comprising a moving conveyor belt, a sign strip riding edgewise thereon in accompaniment therewith, means for holding the sign strip in edgewise arrangement, and means for increasing friction between the belt and sign strip whereby the sign strip is caused to accompany the belt in its movement with a minimum of slippage.

15 4. A device of the class described, comprising a moving belt, a sign strip riding edgewise thereon, the strip having inherent weight which causes it to rest upon the belt with frictional relation between the strip and belt, the tractive effect thus 20 set up urging the strip to accompany the belt in its movement, and means on the strip increasing said tractive effect.

25 5. A device of the class described comprising a moving belt, a sign strip resting edgewise thereon, the strip having inherent weight which causes it to rest upon the belt with frictional relation 30 between the strip and belt, the tractive effect thus set up urging the strip to accompany the belt in its movement, and means on the belt increasing said tractive effect.

35 6. A device of the class described comprising a moving conveyor belt having parallel strands running in opposite directions, a sign strip having a portion riding edgewise on each strand of the belt in frictional contact therewith and means supporting the sign strip in edgewise position with respect to the belt.

40 7. A device of the class described comprising a moving conveyor belt having parallel strands moving in opposite directions, a sign strip riding edgewise on each of said strands in accompaniment with said belt and means supporting the sign strip in edgewise position with respect to the belt.

45 8. For a device of the class described, a sign strip specially prepared to be transported upon and in accompaniment with a conveyor, said strip having means adapted to increase traction between the strip and belt, whereby the strip is caused to accompany the belt with a minimum of slippage.

50 9. For a device of the class described, a sign strip specially prepared to be transported upon and in accompaniment with a conveyor, said strip having means attached thereto increasing traction between the strip and belt beyond that pro-

vided by the normal friction existing as a result of the inherent weight of the strip.

10. A sign device having in combination a moving conveyor consisting of parallel strands moving in opposite directions corresponding to forward and return movement, a sign strip riding edgewise on the conveyor and means to transfer the strip from one strand to the other to cause forward and return movement of the sign strip.

15 11. A sign device having in combination a moving conveyor consisting of parallel strands moving in opposite directions corresponding to forward and return movement, a sign strip riding edgewise on the conveyor means for holding the strip in edgewise arrangement and means to 20 transfer the strip from one strand to the other to cause forward and return movement of the sign strip.

25 12. A sign device having in combination a moving conveyor consisting of parallel strands moving in opposite directions corresponding to forward and return movement, a sign strip riding in edgewise arrangement on the conveyor, said strip being transferable from one strand of the conveyor to the other to be transported by the conveyor in forward and return directions.

30 13. A sign device having in combination a moving conveyor consisting of parallel strands moving in opposite directions corresponding to forward and return movement, a sign strip having portions riding in edgewise arrangement on each of said strands, and in longitudinal alignment therewith, the strip adapted to be transported in forward and return directions in accompaniment with said strands and means automatically retaining the strip in predetermined position with respect to the conveyor.

35 14. A device of the class described comprising a frame, a sign movable in opposite directions in the frame and having a portion that is visible during movement in one of said directions, a moving conveyor upon which the visible portion rides and means to drive the conveyor.

40 15. A device of the class described comprising a frame, a sign movable in the frame having a visible portion, a moving conveyor upon which the visible portion rides, there being frictional contact between the sign and conveyor causing the sign to move with the conveyor.

45 16. A device of the class described comprising a frame, a sign strip disposed longitudinally of the frame, a moving support for the strip between the ends of the frame, and means on the strip preventing the material of the strip from contacting said support.

55 FRANK S. HEBDEN.
